[57] CLAIM

The ornamental design for a combined jar and closure, as shown and described.

DESCRIPTION

FIG. 1 is a front elevation of a combined jar and closure showing my new design, the rear elevation is the same; FIG. 2 is a right side elevation thereof, the left side elevation is the same;

FIG. 3 is a top plan view thereof;

FIG. 4 is a front elevation of a second embodiment of the combined jar and closure, the rear elevation is the same;

FIG. 5 is a right side elevation of FIG. 4, the left side elevation is the same;

FIG. 6 is a top plan view of FIG. 4;

FIG. 7 is a front elevation of a third embodiment of the combined jar and closure, the rear elevation is the same; FIG. 8 is a right side elevation of FIG. 7, the left side elevation is the same;

FIG. 9 is a top plan view of FIG. 7;

FIG. 10 is a front elevation of a fourth embodiment of the combined jar and closure, the rear elevation is the same;

FIG. 11 is a right side elevation of FIG. 10, the left side elevation is the same;

FIG. 12 is a top plan view of FIG. 11;

FIG. 13 is a front elevation of a fifth embodiment of the combined jar and closure, the rear elevation is the same; FIG. 14 is a right side elevation of FIG. 13, the left side elevation is the same;

FIG. 15 is a top plan view of FIG. 13;

FIG. 16 is a front elevation of a sixth embodiment of a combined jar and closure, the rear elevation is the same; FIG. 17 is a right side elevation of FIG. 16, the left side is the same; and,

FIG. 18 is a top plan view of FIG. 16.

The broken line showing of quantitative measurement indicators is for illustrative purposes only and does not form part of the claimed design. The bottom of the jar in each of the embodiments is plain and unornamented.
